UNITED STATES PATENT OFFICE.

CHARLES S. SMITH, OF MILWAUKEE, WISCONSIN, ASSIGNOR TO A. O. SMITH CORPORATION, OF MILWAUKEE, WISCONSIN, A CORPORATION OF NEW YORK.

METHOD OF MAKING AXLE HOUSINGS.

Application filed August 3, 1922. Serial No. 579,479.

The invention relates to rear axle housings and differential gear casings made from sheet steel stampings, pressed into the shape of complementary half-shell members, and welded along their meeting edges into an integral and unitary structure, and pertains particularly to the provision of means whereby the structure is integrally strengthened in certain areas which are subjected to unusual strains. For convenience of description, the axle housing and gear casing will be referred to hereinafter as the housing.

In practicing my improved method of manufacturing, I produce contoured blanks by the dies of a punching press, as usual. The blank is then subjected to oppositely exerted edgewise pressures adjacent the contour lines which define the openings in the sides of the housing. The exertion of such pressures acts to compress the metal of the blank contiguous to the said contour lines, with the result that the gauge of the metal is increased in the areas of such pressures.

The contoured blanks thus treated are pressed into shape as half-shell members, two of which are assembled edge to edge and welded along their meeting lines. In this manner, the housing is provided with integrally formed thickened portions in the region of the openings in its flat sides presenting sufficient body for the required purposes, and which may be drilled without encountering the troubles attendant upon the production of housings of the older form, in which additional metal in the form of separate rings is arranged in conjunction with the openings.

Novel features residing in the invention will be specifically described later on in this specification, and pointed out in the appended claims.

In the drawing herewith:

Fig. 1 is a diagrammatical plan view showing the edgewise compression operation to which the contoured blank is subjected in accordance with my invention.

Fig. 2 is a sectional view on the line 2—2, Fig. 1, showing the action of the clamping dies for preventing displacement of the central area of the blank, and showing also the action of the dies which compress the edges of the blank so as to increase the gauge of the stock in the sections where additional

body is desired for the purposes of my invention.

Fig. 3 is a transverse section of the blank after the same has been subjected to edgewise compression to produce the desired additional body by dies arranged as in Fig. 2.

Fig. 4 is a sectional view differing from Fig. 2, in the arrangement of the compression dies employed.

Fig. 5 is a transverse section of the blank after compression by the dies arranged as in Fig. 4.

Fig. 6 is a view in elevation of an improved housing, broken off at one end, produced in accordance with my invention.

Fig. 7 is a vertical sectional view on the line 7—7, Fig. 6, showing the integral structure of my improved housing.

The flat blank 20 may be heated in its central area, if desirable, and clamped between the dies 25 and 26 of a suitable press, the clamping faces of such dies being of less width than the blank, and cut out as at 27 to constitute matrices into which the margins of the metal blank are adapted to be expanded transversely of the plane of the blank by the pressure exerted against the edges thereof, so as to fill such matrices and thicken the metal at those points. The clamping faces of the dies act to preserve the plane of that portion of the blank which is clamped between them. The bed 29 of the press may be channeled as at 30, corresponding to the outlines of the blank, as shown in Fig. 1, so as to receive the blank and resist its tendency to elongate under the lateral pressure applied to the edges of its central section. Such lateral pressure is effected by means of oppositely working dies 31 and 32, arranged in the same plane, and adapted to bear upon the edges of the blank at its central section, to cause the softened metal to flow transversely of the plane of the blank into and fill the matrices, and thus form the edges of the central section of the blank 20 with side margins 33 of increased gauge, as in Fig. 3, the thickened margins extending along both sides of the blank for the desired distance to constitute a segmental embossment contributing to the formation of a circular rib in the completed housing.

Fig. 4 shows an arrangement of the dies designed to produce a like blank somewhat

modified in cross section and as illustrated in Fig. 5, the thickened margins appearing as ribs 33^a upon one side only of the blank 20, as will be understood from the drawing. 5 This result is produced by forming the lower clamping die as a plane surface, but forming the matrix in the upper clamping die as before described.

The blanks produced in accordance with 10 my new method will be subjected to the action of a drawing press to form the semi-tubular half-shell members, arched transversely at the center, as usual. Complemental members constituting a pair are joined by 15 electrically welding them together along the line of their meeting edges, to produce the integral housing structure 23, with reduced tubular ends and an enlarged central vertical section, shown in Fig. 6. Fig. 7 emphasizes 20 the integral increase in the gauge of the stock, whereby an additional body of metal surrounding the transverse, central, gear assembling openings in the flat sides of the housing is produced, which may be drilled 25 without encountering the difficulties which heretofore have proved to be inseparable from the former methods of manufacture.

I have found that the best results are secured by heating the blank prior to applying 30 the pressures to increase the gauge, but it will be understood that certain grades of steel may be worked without being subjected to prior heat treatment.

It is expedient to form the half-shell members as counterparts, and to weld them together at their meeting edges in the horizontal plane or neutral axis of the axle, inasmuch as the strain in that line is the least to which the housing is subjected. A single 40 set of dies will therefore produce both of the complemental parts of the housing, which parts when welded together as described are united into a single, integral and permanent structure. By "integral" as used in connection 45 with the comprehensive references to the housing in this specification and the claims which are appended, I mean to define a housing as a single element in which the integrity of the metal forming the same 50 is unbroken, and in which there is a homogeneous and inseparable formation, such as is produced by complete arc welding, in which the strength at the point of union is not less than of the materials in which it is 55 formed. The integral housing may therefore be produced by electrically welding together a plurality of shaped parts, or a single shaped part having but one line of weld, or

by the expansion of a seamless or other tube to the varying diameters desired. The other 60 relation in which the term is specifically used carries its own explanation.

Having thus described my invention, what I claim and desire to secure by Letters Patent 65 of the United States, is:

1. The process of making axle housings and gear casings for automobiles, which process comprising the operations of cutting a contoured metal blank, thickening the side margins of the central portion thereof by 70 exerting edgewise pressure thereon, pressing the blank into a semi-tubular formation arched at its center, and welding a pair of the latter along their meeting edges, to produce as an integral structure an elongated 75 tubular housing having reduced ends and an enlarged vertical central section with gear assembling openings in the sides thereof, and with an integrally thickened gauge in the metal of the housing in proximity to the said 80 central openings.

2. The process of making axle housings and gear casings for automobiles, which process comprises the steps of cutting a contoured blank from a metal sheet, subjecting 85 the edges of the central portion thereof to pressures exerted transversely of the blank to reduce its width, pressing the blank into a hollow formation arched at its center, assembling a set of such parts with their edges 90 abutting, and electrically welding them together along their meeting lines, to produce as an integral structure an elongated tubular housing with a widened central section having gear assembling openings in its sides and 95 reduced ends extending oppositely from the central section, and with the metal of the housing integrally thickened in the regions of the said openings.

3. The process of making axle housings 100 and gear casings, which comprises the operations of heating a blank, confining the blank against longitudinal expansion, applying pressure to the edges of the heated section to cause the metal in the margins of the heated 105 section to flow transversely of the plane of the blank, drawing the blank into a semi-tubular formation arched in its central section, and welding a pair of drawn parts at their meeting edges, to constitute an integral tubular housing with a transverse central opening 110 integrally strengthened at its borders.

In witness whereof, I have signed my name at Milwaukee, Wisconsin, this 20th day of July, 1922.

C. S. SMITH.
